UNITED STATES PATENT OFFICE.

HENRY W. O'DOWD, OF JERSEY CITY, NEW JERSEY, ASSIGNOR TO WILLIAM M. CRANE COMPANY, A CORPORATION OF NEW YORK.

SAD-IRON.

1,134,552.

Specification of Letters Patent.

Patented Apr. 6, 1915.

Application filed August 17, 1912. Serial No. 715,563.

To all whom it may concern:

Be it known that I, HENRY W. O'DOWD, a citizen of the United States, and a resident of Jersey City, county of Hudson, and State 5 of New Jersey, have made certain new and useful Improvements in Sad-Irons, of which the following is a specification.

The invention relates to sad irons, and more particularly to that kind of sad iron 10 which is heated by a gas burner contained in the iron.

Objects of the invention are to provide an improved device of the character referred to which, while simple and durable in construction, shall be highly efficient and economical and safe in operation.

These and other objects of the invention will in part be obvious and in part more fully explained in the following description.

20 The invention consists in the novel parts, improvements, combinations, and features of construction herein shown and described.

In the accompanying drawings, which are referred to herein and form a part hereof, 25 is illustrated an embodiment of the invention, the same serving in connection with the description herein to illustrate the principles of the invention.

Of the drawings: Figure 1 is a perspective 30 view of an embodiment of the invention; Fig. 2 is a vertical central section of the same, parts being shown in perspective; Fig. 3 is a perspective view of a detail; and Fig. 4 is partly a plan view taken on the line 35 4—4 of Fig. 2 and also shows certain parts in perspective.

A sad iron constructed in accordance with certain features of the invention comprises in combination, a casing forming a chamber, 40 a base having transverse corrugations, a plurality of said corrugations being hollow to form air passages and having openings in their upper portions to admit the air to said chamber, and a burner arranged longitudinally in said chamber and above said corrugations, said burner having perforations arranged therein to direct the flame downward between said corrugations.

According to other features of the invention, 50 a plate is arranged at the bottom of said chamber and said plate is corrugated, the plate being cast with the ridges of the corrugations hollow as above set forth; the sides and rear wall of the casing are formed 55 with openings therein for the escape of the

heated products of combustion, said openings being of sufficient capacity to set up a circulation; a hinged top is provided for the iron; and an air-mixing tube is provided for the burner.

Referring now to the drawings in detail, the embodiment of the invention illustrated comprises a casing 6 of the usual configuration and forming a chamber 7. Into this chamber is introduced through an orifice 8 60 in the rear wall of the casing a burner 9 of the Bunsen type, the air mixing tube 10 of which is arranged outside of the casing and is connected in a usual manner with the flexible gas tube, not shown. While the 65 burner 9 may be arranged in the said chamber in a variety of ways, preferably and as shown, it extends longitudinally and centrally in a horizontal plane of the chamber, being held in place forward by a piece 12 70 fitting into a correspondingly shaped recess in the front of the casing. The burner is supported also on lugs 13 and 14 of suitable height and situated, respectively, at the opposite ends of the chamber 7, and to these 75 lugs some further allusion will be made.

As shown, the burner 7 and mixing tube 10 are joined by a flange 16, suitably recessed for that purpose, said flange being 80 suitably secured, as by screw 17, at its top to the rear wall of the casing. To prevent the heating of the mixing tube 10 by the burner 9, preferably a gasket 18 of suitable insulating material, as asbestos, is disposed between the rear wall of the casing and the 85 flange 16. In order that the base of the 90 said iron may be heated to the best advantage, the burner 9, preferably and as shown, is formed with a plurality of perforations 95 19 in its under side, to which further reference will presently be made.

Means are provided for supplying air to the burner 9 to maintain combustion. This means comprises a plurality of air passages formed in the base of the casing and arranged transversely of the chamber 7 at suitable intervals and having openings so disposed as to supply at points adjacent to the perforations 19 of the burner atmospheric air conducted through said passages. While these air passages may be provided in various ways, preferably and as shown, a plate 20 conforming in outline to the walls of the chamber 7 is placed in the bottom of 100 said chamber, the said lugs 13 and 14 which 105 110

are formed on said plate serving not only as supports for the burner 9 but also to keep said plate in position. As shown, also, said plate 20 is corrugated transversely to form alternate furrows 22 and ridges, which latter are cast hollow to form the air passages 21, openings 23 being formed in the side walls of the casing 6 in register with the air passages 21. The ridges also have suitable openings 25 in the center thereof, through which the atmospheric air enters the chamber 7. The perforations 19 hereinbefore referred to are so disposed on the under side of the burner 9 that their flames are directed into the furrows 22 and the heat is thus imparted quickly and without waste to the bottom of the iron.

Suitable vents for the waste products of combustion are provided, the same, preferably and as shown, consisting of openings 27 formed in the upper side and rear walls of the casing 6. It is to be noted that these openings are of sufficient extent to afford a capacity equal to the demands of the burner 25 with its primary and secondary air supplies and thus maintain a proper circulation.

The casing is provided with a hinged top 29 which is suitably secured to the casing, as by means of hinges 30 and the thumb screw 32 which operates in registering openings in the top and casing and which projects inwardly over the said top, as shown in Fig. 2, and this holds said top in position. As also shown, a handle 33 is removably secured to the top 29, as by thumb screw 35, which operates in suitable recesses in the handle and top, lugs 36 and 37 being also provided on the handle which fit in suitable recesses in the top 29 and thus steady the handle.

It will be seen that a sad iron constructed in accordance with the invention will carry out the objects of the invention, as heretofore set forth, and will possess other advantages which will be apparent to those skilled in the art.

The invention in its broader aspects is not limited to the precise construction shown and described, as many changes may be made in the details thereof without departing from the main principles of the invention or sacrificing its chief advantages.

I claim:

1. A sad iron including in combination, a casing forming a chamber, a base having transverse corrugations, a plurality of the ridges of said corrugations being hollow to form air passages and having openings in their upper portions to admit the air to said chamber, and a burner located longitudinally of said chamber and above said corrugations, said burner having perforations arranged therein to direct the flame downward between said corrugations.

2. A sad iron including in combination, a

casing forming a chamber, a base having transverse corrugations, a plurality of the ridges of said corrugations being hollow to form air passages and having openings in their upper portions to admit the air to said chamber, a burner located longitudinally in said chamber and above said corrugations, said burner having perforations arranged therein to direct the flame downward between said corrugations, and vents in the upper portion of said casing.

3. A sad iron including in combination, a casing forming a chamber, a base having transverse corrugations, a plurality of the ridges of said corrugations being hollow to form air passages and having openings in their upper portions to admit the air to said chamber, and a burner located longitudinally and midway transversely of said chamber and above said corrugations, said burner having perforations arranged therein to direct the flame downward between said corrugations.

4. A sad iron including in combination, a casing forming a chamber, a base having transverse corrugations, a plurality of the ridges of said corrugations being hollow to form air passages and having openings in their upper portions to admit the air to said chamber, and a burner located longitudinally of said chamber and above said corrugations, said burner having perforations disposed therein at points between the ridges of said corrugations to direct the flame downward between said ridges.

5. A sad iron including in combination, a casing forming a chamber, a base having transverse corrugations, a plurality of the ridges of said corrugations being hollow to form air passages and having openings in their upper portions to admit the air to said chamber, a burner located longitudinally in said chamber and above said corrugations, said burner having perforations arranged therein to direct the flame downward between said ridges, and vents in the upper portions of said casing, said vents having capacity equal to the capacity of the burner and air inlets.

6. A sad iron including in combination, a casing forming a chamber, a plate arranged in the bottom of said chamber and having corrugations extending between the sides of the iron, a plurality of the ridges of said corrugations forming air passages and having openings to admit the air to said chamber, said casing having openings formed in its sides in register with the said air passages, and a burner having perforations arranged therein to direct the flame downward between said ridges.

7. A sad iron including in combination, a casing forming a chamber, a plate arranged in the bottom of said chamber and having corrugations extending between the sides

- of the iron, a plurality of the ridges of said corrugations forming air passages and having openings to admit the air to said chamber, said casing having openings formed in 5 its sides in register with said air passages, said burner having perforations arranged therein to direct the flame downward between said ridges, and vents in the upper portion of the casing.
- 10 8. A sad iron including in combination, a casing forming a chamber, a plate arranged in the bottom of said chamber and having hollow corrugations extending from side to side of the iron, a plurality of said corruga- 15 tions forming air passages and having open- ings in their upper portions to admit the air to said chamber, said casing having open- 20 ings in its sides in register with the said hollow corrugations, and a burner arranged longitudinally of said chamber above said hollow corrugations, said burner having perforations arranged therein at points be- 25 tween the ridges of said corrugations to di- rect the flame downward into the grooves of said corrugations.

Copies of this patent may be obtained for five cents each, by addressing the "Commissioner of Patents,
Washington, D. C."

9. A sad iron including in combination, a casing forming a chamber, a burner ar- ranged longitudinally in said chamber, air passages extending transversely of the bot- 30 tom of and admitting air to said chamber, spaces between said air passages, and perfora- tions disposed in said burner to direct the flame downward into the said spaces be- tween said air passages.

10. A sad iron including in combination, 35 a casing forming a chamber, a base having transverse corrugations, ridges of said cor- rugations forming passages for the admis- sion of air to said chamber, and a burner ar- ranged longitudinally in said chamber 40 and having downwardly disposed perfora- tions located between said ridges.

In testimony whereof, I have signed my name to this specification, in the presence of two subscribing witnesses.

HENRY W. O'DOWD.
